B. BRODIO.
SUPERHEATER HEADER.
APPLICATION FILED SEPT. 16, 1918.

1,338,972.

Patented May 4, 1920.

BENJAMIN BRODIO Inventor

By HIS Attorney O. V. Thiele

UNITED STATES PATENT OFFICE.

BENJAMIN BRODO, OF NEW YORK, N. Y., ASSIGNOR TO LOCOMOTIVE SUPERHEATER COMPANY, OF NEW YORK, N. Y., A CORPORATION OF DELAWARE.

SUPERHEATER-HEADER.

1,338,972.

Specification of Letters Patent.

Patented May 4, 1920.

Application filed September 16, 1918. Serial No. 254,306.

To all whom it may concern:

Be it known that I, BENJAMIN BRODO, a citizen of Russia, and resident of New York, N. Y., have invented certain new and useful Improvements in Superheater-Headers, whereof the following is a specification.

The invention forming the subject of this application relates to superheater headers which have the superheater elements on units secured to them by means of some form of clamp which forcibly holds an enlarged head on the end of the element in engagement with a corresponding seat in the header; and has for its object the provision of means stiffening and strengthening the header against the external pressure exerted by the clamp, so that headers of thinner walls can be used than would otherwise be the case.

In the drawing accompanying this and forming part hereof, Figure 1 is a sectional elevation on line 1—1 of Fig. 2 of a header with the attached units or elements according to my invention; Fig. 2 is a sectional view on line 2—2 of Fig. 1; Figs. 3 and 4 are views, similar to those of Figs. 1 and 2, of a modification; Figs. 5, 6 and 7 are sectional views similar to the view of Fig. 2, of other modified forms. Throughout the drawing, parts have been broken away where it appeared desirable and could be done without loss of clearness.

Referring first to Figs. 1 and 2, there are shown two headers, 1 and 2, arranged parallel to each other. These headers are made up of tubing, such as can be readily obtained in the market. By means of my invention piping of ordinary gage can be used, whereas without it the heaviest piping made may in some case be too weak.

To the bottom of each header is welded a strip 3. At proper intervals holes 4 are drilled through the plates and pipes, the outer ends of the holes being suitably chamfered, as at 5, to form seats which are engaged by the spherical surfaces of the enlarged ends 6 of the superheater elements 7. Engaging the lower sides of the ends 6 are washers 8. The two ends of each unit pass through circular openings in the clamp 9, one opening being near each end of the clamp. The washers 8 rest on the clamp. A bolt 10 passes through a central opening of each clamp 9, its head 11 engaging the under surface of the clamp. The opposite end of the bolt passes through an opening in bar

12 and has threaded on it the nuts 13 and 14, the former engaging the upper surface of bar 12. The bar 12 rests on the two headers 1 and 2.

It will be clear that by pulling up nut 13 the enlarged heads 6 of the elements 7 will be held firmly against the seats 5 in the bars 3.

This arrangement of headers and attached elements has various applications, but the one more immediately under contemplation is to steam superheaters. The elements 7, when the device is put to this use, extend into some space where hot gases sweep over them, and steam passing through them from one header to the other has transferred to it some of the heat from the gases. In such use particularly it is important that the joint between heads 6 and their seats 5 be tight. When the nuts 13 are tightened to effect such tight joints, the pipe of which the headers 1 and 2 are made is very apt to be deformed unless it is of the heaviest gage made. Moreover if any one clamp is tightened the consequent flattening of the header will tend to loosen the adjacent joints. To obviate these difficulties and yet make possible the employment of pipes of thinner gages, I introduce a system of bracing which I shall now describe.

Between adjacent holes 4 I place pipe-lengths 15 extending diametrically through the header and bearing against opposite portions of the wall. The ends of the pipe lengths are milled or otherwise machined to the proper radius to engage the rounded surface of the pipe. To facilitate the placing of these pipe lengths and obviate their dislocation I employ two holders 16—16 for each header. These consist each of a flat bar with appropriately spaced and suitably sized apertures into which the pipe lengths 15 are slipped. If required to keep these holders in their proper location they may each be spot-welded to two of the pipe lengths; or they may be retained in their proper relative position by means to be described in connection with Fig. 3.

These pipe-lengths 15 effectually serve to prevent the pipe forming the header from being distorted by the pressure of the clamps. When any one clamp is tightened up there will be no tendency to loosen adjacent joints; in fact, the opposite tendency will be seen to exist, since the ends of the pipe-lengths will act as fulcrums and the

tendency will be to cause the areas beyond them to bulge outward, with the result that the adjacent joints will be made tighter.

5 The pipe-lengths 15 being mounted in the bars 16 their insertion into the header, or withdrawal from it is effected through the end of the header and is evidently a very simple matter.

10 Instead of being placed between neighboring holes 4 as described, the pipe-lengths 15 may be placed directly on these holes as shown in Figs. 3 and 4. In this case openings 17 are provided in the pipe-lengths, establishing communication between the interior of the header and the elements 7. These openings may be of any desired shape or disposition, but should of course be large enough to accommodate the steam flow. The bars 16 are shown, by way of possible 15 variation, as held at their proper relative distance by the bolt 18 and nuts 19, one such bolt being placed at either end.

20 The function of this form of my device will be understood from the above description. There is one advantage which this variation possesses over the one first described, *i. e.* the steam distribution between the several units can be equalized or generally controlled by varying the holes 17 30 suitably.

To illustrate that my invention has application to other shapes of headers than cylindrical ones, I have shown it in Figs. 5, 6 and 7 applied to headers of three different forms.

35 In Fig. 5, the headers are D-shaped in cross-section and are placed with their flattened sides 20 toward each other. This has the advantage that with the headers placed 40 apart a distance sufficient for the passage of bolts 10 the element ends 5—5 are not so far apart as they are in the form first described, and the clamps 9 and bars 12 are correspondingly shorter. The only variation, as far as the pipe-lengths 15 are concerned, is that their ends are squared, instead of rounded, so as to bear properly on the flat portions of the headers which they engage.

45 The headers of Fig. 6 are made up of two angles 21—21 each, welded together at their edges. The application of the pipe-lengths 15 will be apparent.

In Fig. 7 the headers are made up each 50 of a plate 22 bent into a cross-sectionally U-shaped form, to the edges of which is welded the flat plate 23. This form needs no further description.

Evidently these headers may be modified 55 in other ways. For example in the form of Fig. 5, the curved portion of the wall may be enlarged laterally as much as desired, or it may be distended also upwardly and downwardly as well as laterally, so that it becomes in effect circular with a lateral chan-

nel. As long as the interior bracing according to my invention is used, I consider such forms to fall within my invention idea and to come within the scope of the appended claims.

70 While I have described and shown in the drawing only one form of joint between the ends of the elements and the headers, it will be clear that this is not intended as a limitation, and that other forms, *e. g.*, with 75 gaskets, may be used.

What I claim is:

1. In apparatus of the class described, the combination of a header; a superheater element; means to hold said element in engagement with said header, said means exerting external pressure on opposite walls of said header; and internal means resisting such pressure.

2. In apparatus of the class described, the combination of a header having a plurality of openings in one of its walls; a plurality of tubular superheater elements whose ends are adapted to engage said openings; means to keep said ends in engagement with said 90 openings, said means exerting external pressure on the wall having the openings and the wall opposite it; and means engaging the interior of said walls resisting such pressure.

3. In apparatus of the class described, the combination of a header having in one of its walls a plurality of openings each formed with a seat; a plurality of tubular superheater elements whose ends have enlarged heads adapted to engage said seats; clamping means bearing on the enlarged heads and on the opposite wall of the header; and means comprising lengths of pipe engaging the interior of said opposite 105 walls resisting the pressure of the clamping means.

4. In apparatus of the class described, the combination of a header having in one of its walls a plurality of spaced, alined openings each formed with a seat; a plurality of tubular superheater elements whose ends have enlarged heads adapted to engage said seats; clamping means bearing on the enlarged heads and on the opposite wall; short 110 lengths of pipe placed between said openings and engaging the interior of the apertured wall and the wall opposite it; and means to keep said pipe-lengths in their relative positions.

5. Means to reinforce a header of the class described against external pressure on two of its opposite sides comprising a plurality of pipes of suitable length with their ends shaped to engage the interior of the opposite walls, and means holding them relatively fixed so they can be inserted or withdrawn as a unit.

BENJAMIN BRODIO.
